(57) **CLAIM**

The ornamental design for a drinks machine, as shown and described.

DESCRIPTION

FIG. 1 is a first perspective view of a drinks machine showing my new design;

FIG. 2 is a second perspective view of the drinks machine shown in FIG. 1;

FIG. 3 is a front view of the drinks machine shown in FIG. 1;

FIG. 4 is a rear view of the drinks machine shown in FIG. 1;

FIG. 5 is a right side view of the drinks machine shown in FIG. 1, the left side view being a mirror image of the right side view of the drinks machine;

FIG. 6 is a top view of the drinks machine shown in FIG. 1; and,

FIG. 7 is a bottom view of the drinks machine shown in FIG. 1.

The broken lines in the drawing views are included for the purpose of illustrating unclaimed environment only, and forms no part of the claimed design.
